UNITED STATES PATENT OFFICE

2,047,986

COMPRESSOR

Wade H. Wineman, Michigan City, Ind., assignor
to Sullivan Machinery Company, a corporation
of Massachusetts

Application September 29, 1934, Serial No. 746,169

10 Claims. (Cl. 230—108)

My invention relates to gaseous fluid compressors, and more particularly to gaseous fluid compressors in which a liquid is employed under the action of centrifugal force as the gas compressing medium.

From one of its aspects my invention relates to the provision of a gaseous fluid compressor in which a liquid, after having had a large amount of energy imparted to it in the course of its action as the compressing medium and while, furthermore, under the pressure existing at the discharge side of the compressor, is so handled as to cause the same to give up its energy, and to impart the maximum available energy to the driving system for the compressor. From another aspect of my invention the same comprises the feature of employing in a liquid compressor system a separating device in conjunction with the compressor of such nature that the kinetic energy of the liquid flowing from the discharge side of the compressor is largely preserved and made available for delivering work to the driving system of the compressor. From still another aspect my invention comprises the employment, in a liquid compressor system, of a very effective air separating mechanism which, like the compressor, operates upon the centrifugal principle and which preserves and makes available energy present in the liquid when it enters the separator.

An object of my invention is to provide an improved fluid compressor. Another object of my invention is to provide an improved fluid compressor of the centrifugal type. Still another object of my invention is to provide an improved fluid compressor of the centrifugal type having improved compressing-liquid handling means incorporated therein. Still another object of my invention is to provide an improved combination of a hydraulic centrifugal compressor and an improved hydraulic separator. Yet another object of my invention is to provide an improved combination of a hydraulic centrifugal compressor, a centrifugal separator, and a hydraulically-actuated power economizing device for the compressor drive. Other objects and advantages of my invention will hereinafter more fully appear.

In the accompanying drawings in which one illustrative form of the invention has been shown,—

Fig. 1 is a plan view of a compressor system in which the illustrative embodiment of the invention is incorporated.

Fig. 2 is a view partially in side elevation and partially with parts broken away showing the same system.

Fig. 3 is a view at right angles to the view of Fig. 2, showing a section through the compressor proper.

Fig. 4 is a vertical section upon the plane corresponding to the line 4—4 of Fig. 3.

Fig. 5 is a fragmentary section through a Pelton wheel.

Fig. 6 is a face view of a Pelton wheel bucket.

Fig. 7 is a bottom view of one of the Pelton buckets, the view being taken on the plane corresponding to the line 7—7 of Fig. 6.

Referring to the drawings, it will be observed that a base 1 is provided in the form of a large hollow tank in which water 2 or other suitable compressing medium is employed. Desirably, a suitable cooling means in the form of a radiator or the like immersed in the water may be provided, or the water in the tank can be changed if that be found more practicable. Upon the tank 1 there is mounted upon a suitable support 3 a driving motor 4, herein an electric motor, and in alignment with the motor there is mounted a compressor 5 of the hydraulic, centrifugal type. The motor shaft 6 is connected through a suitable flexible coupling 7 with the shaft 8 of the compressor, and the latter carries a rotor 9 which is provided with a series of generally radially extending passages 10, 11 at opposite sides of a central fin member 12. The passages 11 communicate with an annular intake space 14 to which air or other gas to be compressed is admitted through a suitable connection 15. The passages 10 are adapted to be supplied with a liquid (herein in the water from the tank 1) from a supply chamber 16 which communicates with a supply space 17 connected by a suction pipe 18 with the interior of the tank 1. Suitable means for priming the pump may be employed in starting it up, if desired or needed. The passages 10 and 11 unite in a circumferential zone 20, the fast moving liquid drawing in the air through the passages 11, and the mixture, with the air duly compressed being discharged into a stationary raceway 21 which leads to the point of compressor discharge. The zone 20 may be annular or broken up into a series of chambers extending radially and communicating with the spaces 10 and 11 at their inner sides and with the raceway 21 at their outer sides. From the raceway 21 a connection 22 leads tangentially into the upper portion of a centrifugal separator chamber 23 in which, under the action of centrifugal force, a very complete and effective separation of the entrained and compressed air from the compressing medium takes place. The liquid within the chamber

23, shown at 24, whirls rapidly around within the chamber and is permitted to return from the bottom of the chamber through a connection 25 formed to conserve the velocity of the liquid, to 5 a nozzle element 26 in the same horizontal planes with the lower portion of a Pelton wheel 27, which is secured to an extension 28 of the compressor shaft 8. The buckets 29 of the Pelton wheel are acted upon by the liquid discharging through the 10 nozzle 26, so that the wheel aids the motor in effecting drive, as it were, and thereafter the liquid falls into a sump 30 and returns through a connection 31 to the tank 1. The liquid level in the separator 23 can obviously be controlled by the 15 use of suitable manual or automatic valves, if desired, but it is evident that the liquid can pass out of the chamber at least as rapidly as the mixture enters, and since the Pelton wheel is on a smaller radius than the orifices at the periphery 20 of the compressor rotor the liquid discharge velocity will be amply high.

The mode of operation of my improved compressor mechanism will be readily understood from what has been said with respect to its construction. The motor 4 will be started and, if desired, the compressor may be primed, although this will not be necessary if the lift from the water level in the tank 1 to the chamber 17 is small. Thereafter the liquid will be constantly drawn 30 into the chamber 17 and will pass outwardly through the runner of the pump through the chambers or passages 10 and will suck in at the point of junction of these passages with the passages 11 with an aspirating action the gaseous 35 fluid to be compressed as the latter is drawn in through the passage 15, chamber 14, and passages 11. The liquid will then compress the aspirated fluid and the mixture will pass into the raceway 21, whence it will be delivered at high velocity 40 through the pipe 22 to the upper part of the separating chamber 23. The fluids entering the separating chamber will then separate from each other, the heavier water or other liquid compressing 45 medium traveling around the periphery of the separating chamber and the lighter air being squeezed into the center and out of the liquid. As a result, a very effective separation will take 50 place and the air may be conducted, if desired, at the designed terminal pressure through a discharge connection 32. The liquid, however, will continue to whirl rapidly in the casing 23 and will flow out tangentially through the connection 25 to the nozzle 26 and engage the runner of the Pelton wheel and as the latter is of smaller 55 diameter than the circle of discharge of the compressor rotor will transmit a rotary force to the compressor driving shaft at the necessary speed effectively to cooperate with the driving motor 4 in driving the compressor.

60 From the foregoing description it will be evident that I have provided a very effective, simple, relatively inexpensive, and practicable compressor plant, avoiding losses of power inherent in many hydraulic type compressors and insuring, 65 moreover, a very effective separation of the air and a cooling of the latter by the compressing medium. It will be noted, moreover, that the air passing through the compressor is washed, and accordingly this apparatus is well adapted for incorporation in an air conditioning system or the like.

70 While I have in this application specifically described one form which my invention may assume in practice, it will be understood that this 75 form of the same is shown for purposes of illus-

tration, and that the invention may be modified and embodied in various other forms without departing from its spirit or the scope of the appended claims.

What I claim as new and desire to secure by 5 Letters Patent is:

1. In combination, in a gas compressing apparatus, a hydraulic centrifugal compressor having a tangential discharge for the liquid compressing medium and the entrained compressed gas, a driving motor for said compressor, a separator having a tangential inlet receiving said liquid and entrained gas and having a tangential discharge for liquid, a rotary hydraulic motor operatively connected in driving relation with the compressor, 10 and means for conducting liquid from said last mentioned tangential discharge to said hydraulic motor.

2. In combination, in a gas compressing apparatus, a hydraulic centrifugal compressor having 20 a tangential discharge for the liquid compressing medium and the entrained compressed gas, a driving motor for said compressor, a separator having a tangential inlet receiving said liquid and entrained gas and having a tangential discharge for liquid, a hydraulic turbine operatively connected in driving relation with the compressor, 25 and means for conducting liquid from said last mentioned tangential discharge to said hydraulic turbine.

3. In combination, in a gas compressing apparatus, a hydraulic centrifugal compressor having a tangential discharge for the liquid compressing medium and the entrained compressed gas, a driving motor for said compressor, a separator having 30 a tangential inlet receiving said liquid and entrained gas and having a tangential discharge for liquid, a hydraulic turbine operatively connected in driving relation with the compressor, 35 and means including a velocity-conserving conductor for conducting liquid from said last mentioned tangential discharge to said hydraulic turbine.

4. In a pumping apparatus, a centrifugal hydraulic compressor having a discharge and having 45 a rotor rotatable upon its axis, a centrifugal separator having an axis disposed at right angles to a line parallel to the axis of rotation of said rotor, said separator having a tangential inlet in the same plane with the central plane 50 of rotation of said rotor and in communication with the compressor discharge, separate liquid and gas discharges for said separator at least one of which is tangential, and a compressor driving element operatively connected with said 55 tangential discharge.

5. In a pumping apparatus, a centrifugal hydraulic compressor having a discharge and having 60 a rotor rotatable upon its axis, a centrifugal separator having an axis disposed at right angles to a line parallel to the axis of rotation of said rotor, said separator having a tangential inlet in the same plane with the central plane 65 of rotation of said rotor and connected with the compressor discharge, and separate liquid and gas discharges for said separator, the former being tangential to and near the bottom of said separator, and means for driving said rotor including a main driving motor and a supplemental water wheel receiving water from said 70 tangential liquid discharge.

6. In a pumping apparatus, a centrifugal hydraulic compressor having a discharge and having 75 a rotor rotatable upon its axis, a centrifugal separator having an axis disposed at right angles

to a line parallel to the axis of rotation of said rotor, said separator having a tangential inlet in the same plane with the central plane of rotation of said rotor and connected with the 5 compressor discharge, and separate liquid and gas discharges for said separator, the former being tangential to and near the bottom of said separator, and means for driving said rotor including a main driving motor and a supplemental 10 water wheel receiving water from said tangential liquid discharge and having a velocity-conserving connection with the latter.

7. In a pumping apparatus, a centrifugal hydraulic compressor having a discharge and having 15 a rotor rotatable upon its axis, a centrifugal separator having its axis vertical, said separator having a tangential inlet in the same plane with the central plane of rotation of said rotor and connected with the compressor discharge, and 20 separate liquid and gas discharges for said separator, the former being tangential to and near the bottom of said separator, and means for driving said rotor including a main driving motor and a supplemental water wheel receiving water 25 from said tangential liquid discharge.

8. In combination, in a pumping apparatus, a compressor driving motor, a hydraulic centrifugal compressor driven thereby and having a rotor rotatable upon a horizontal axis, a centrifugal separator arranged with its axis vertical, a Pelton wheel coaxial with and operatively connected to the compressor rotor, a tangential discharge from the compressor operatively connected with a point adjacent the top of said

separator, and a tangential discharge from said separator leading therefrom adjacent the bottom thereof to a position substantially tangent to said Pelton wheel adjacent the lower side of the latter to drive the same in the direction in which the 5 compressor is driven by its driving motor.

9. In combination, in a gas compressing apparatus, a hydraulic centrifugal compressor having a rotor and a tangential discharge for the liquid compressing medium and the entrained 10 compressed gas, a separator having a tangential inlet in the planes of rotation of said rotor and a lower tangential discharge, said compressor discharge being connected with said separator inlet, driving means for said rotor, and supplemental, power-conserving driving means for said 15 rotor including a water wheel having a nozzle adjacent its periphery and connected with said last mentioned tangential discharge.

10. In combination, in a gas compressing apparatus, a hydraulic centrifugal compressor having a rotor and a tangential discharge for the liquid compressing medium and the entrained 20 compressed gas, a separator having a tangential inlet in the planes of rotation of said rotor and a lower tangential discharge, said compressor discharge being connected with said separator inlet, driving means for said rotor, and supplemental, power-conserving driving means for said 25 rotor including a water wheel having a nozzle adjacent its lower periphery and connected by piping free from right angle turns with said second mentioned tangential discharge.

WADE H. WINEMAN.
